UNITED STATES PATENT OFFICE

JAMES H. GILSON, OF CHICAGO, ILLINOIS.

BATHING CAP.

Application filed June 21, 1923. Serial No. 646,937.

To all whom it may concern:

Be it known that I, JAMES H. GILSON, a citizen of the United States, residing at Chicago, Illinois, have invented certain new and useful Improvements in Bathing Caps, of which the following is a specification.

This invention relates particularly to coverings for the head and more especially to water-proof coverings whereby the hair may be kept dry, and among the objects of this invention are to so improve the construction of such an article that it will reduce the possibility of water getting inside thereof; to provide a cap of larger dimensions than the ordinary cap so that it will go over the head more easily and have more room for hair; to provide a cap having increased wearing qualities, by reason of the elimination of straining, tearing, scratching that occurs when ordinary caps are stretched to put them on; to provide means whereby the head band of such a structure may be drawn taut around the head so as to keep out as much water as possible; to provide means whereby the normal slack of such a head covering may be drawn to the back thereof; to provide means for positively tightening such a construction around the head of the wearer; to provide such a means with an elastic portion whereby the same is held positively tightly against the head; to so construct an object of the character described that the head band will be adjustable to different sized heads; to so construct an object of the character described that there will be no slippage in the adjusting means; to so construct a cap of the character described that the holding means for the tightening straps will normally be invisible; to provide a cap of the character stated having an abundance of room for a woman's hair and yet having a snug fit at its edge; and such further objects, advantages, and capabilities as will later more fully appear.

My invention further resides in the combination, construction and arrangement of parts illustrated in the accompanying drawing, and, while I have shown therein a preferred embodiment, I desire the same to be understood as illustrative only, and not as limiting my invention.

In the drawing annexed hereto and forming a part hereof, Fig. 1 is a side elevation of an embodiment of my invention; Fig. 2 is a fragmentary front elevation of the construction shown in Fig. 1; and Fig. 3 is an

inverted plan view of the structure shown in Fig. 2.

Referring more in detail to the drawing, 1 denotes the main or head covering portion of a cap which is constructed permanently substantially dome-shaped or cup-shaped whereby to fit over and envelop the upper portion of the head of the wearer. The edge of the open mouth of this substantially dome-shaped or cup-shaped cap is provided with an endless band for forming a reinforcing member in accordance with my invention which cap is formed with an endless edge band forming a reinforcing member. This edge band is provided with straps 2 and 3 by means of which the edge of the body portion is tightened around the head. The straps 2 and 3 may be made up of inelastic material, preferably webbing; or may be made of heavy rubber or other material which will stretch but slightly under a moderate pull, and are secured at 4 and 5 respectively. The cap may be drawn tightly around the head by pulling upon the straps. Loops 6, 7 and keepers 8 are secured to the back portion of the body 1, and through these the straps 2 and 3 may slide when the cap is tightened on the head by a pull on the loose ends of straps 2 and 3. The loops 6 and 7 may be of any suitable material, such as metal, celluloid or fabric, which will not stretch, while keepers 8 serve merely as a guide and may be made of any material appropriate for this purpose. All materials are preferably non-rustable. The buttons 14 may be of celluloid, nickelized brass, etc. Fastening members 9 and 10 are secured at the ends of these straps and through these fastening members are passed short pieces 11 and 12, of elastic material, such as rubber straps. Buttonholes 13 or other suitable fastening means are formed in or secured to the ends of the elastic straps 11 and 12 for engagement with buttons 14 or other cooperating fastening parts which are concealed underneath the ends of the bow 15, which bow is preferably made of sheet rubber and serves merely as an ornament and to conceal the fastenings as shown. Fabric reinforcements are preferably used at all attaching points. It will be apparent that the crown of the cap does not need to be made of elastic material, since it is made large enough to go over the wearer's head, but may be made of some material such as waterproof or rubberized silk.

To apply this cap to the head, pieces 11 and 12 are unbuttoned from the buttons 14 and the cap is opened up so it may be easily placed over the head. A pull is then exerted upon the straps 2 and 3 to draw the cap tightly around the head so that it will be substantially impossible for water to find room to pass between the cap and the head. The straps are then adjusted to the size of the wearer's head by pulling the rubber strips 11 and 12 through the buckles 9 and 10. The buttonholes are then placed upon the buttons 14 and the cap will be held securely and tightly in place. When the straps 11 and 12 have been once adjusted no further adjustment is necessary while the cap is being worn by the same person. The straps 2 and 3 being non-elastic, or only slightly elastic, make it possible to draw the cap tightly about the head, while the elastic portions 11 and 12 furnish as much elasticity as is necessary in the ordinary cap. The straps 11 and 12 are slightly greater in width than the fastening devices or buckles 9 and 10 so that they will not slip therethrough, in ordinary use, but they can nevertheless, be adjusted when this is necessary. When tension is placed on the straps 11 and 12 in applying the cap the portion which is stretched is reduced in width to substantially the same width as the straps 2 and 3. When drawn into place with folds in the back, the cap naturally shapes itself to a woman's ordinary hair dress.

In this specification and the appended claims the word "buckles" is used to denote the tongueless, buckle-like members 9 and 10 or their functional equivalents.

It is, of course, understood that the specific description of structure set forth above may be departed from without departing from the spirit of my invention as set forth in this specification and the appended claims.

Having now described my invention, I claim:—

1. A bathing cap comprising a permanently formed substantially dome-shaped body having an endless edge at its open mouth, tightening members secured at their ends adjacent the edge of the open mouth of the body and overlapping each other so that a pull thereon will cause the body portion to be tightened around the head, said members being formed of non-elastic material and

provided at their free ends with elastic extensions, adjustably connected to the non-elastic portions.

2. A bathing cap comprising a body portion permanently formed substantially dome-shaped and having an open mouth, tightening members for said body, said tightening members being secured at their ends adjacent the edge of the mouth of the body and overlapping each other so that a pull thereon will cause the body portion to be tightened around the head, said members being formed of non-elastic material and provided at their free ends with elastic extensions, adjustably connected to the non-elastic portions, the extensions having detachable securing means for securing the free ends of the elastic members to the body portion.

3. A structure of the character described having a body portion formed around its open edge as an endless band, non-elastic straps secured thereto at spaced apart locations and overlapping so that the body may be drawn taut around an object upon which it is placed, said body being provided with securing means and said non-elastic straps being provided with elastic extensions adapted to be detachably engaged with the securing means.

4. A cap comprising a permanently formed substantially dome-shaped body portion having an open mouth, formed with an endless open edge portion, an ornament secured to said body adjacent said edge, securing means fastened to the body member underneath the ornament, and overlapping tightening straps secured to the edge of the body at the side opposite the reinforcing member and adapted to be detachably secured to the securing means.

5. A cap comprising a body portion, having an open mouth the edge portion of said mouth having a reinforcing endless member on which is mounted an ornament, securing means concealed beneath the ornament, and non-elastic means for drawing the edge tight around a person's head, said last named means being provided with elastic extensions adapted to be detachably secured to the said securing means.

In witness whereof, I hereunto subscribe my name to this specification.

JAMES H. GILSON.
